SUPPORTING AND PRESSING BOARD
STRUCTURE FOR IRONING TABLES

William L. Kisling, St. Louis County, Mo.

Application December 16, 1946, Serial No. 716,540

2 Claims. (Cl. 38—107)

1

This invention relates to improvements in pressing tables, and more particularly to an improved supporting and pressing board structure adapted for use with steaming irons, such as, for example, those supports employed in the finishing of woolen and other textiles and fabrics, both before and after fabrication into garments and other products.

In those of the textile industries which require finishing operations particularly of woolen goods and the like, it is the practice to employ steaming irons. Such irons prevalently include a heated sole plate, and provisions for emitting steam through or along the sole plate for the purpose of imparting a certain desirable amount of moisture to the fabric in the course of ironing or pressing. A serious difficulty prevails in that it is usually desirable to employ a resilient pressing surface, usually of some fibrous material, which tends after a short period of finishing operations, to become at least partially saturated with the condensate from the steaming iron. According to prevailing practice under these difficulties the pressing boards are either kept out of service for considerable periods of time for drying, or alternately, are employed in soggy condition, thus seriously impairing the quality of the work. The present invention has accordingly a prime objective of eliminating the noted difficulties by providing for evaporation of condensate otherwise accumulating in the pressing support, thus removing unwanted moisture at a rate equal to that of its accumulation.

A further and important object is attained in an ironing support or table in which the pressing surface is maintained at all times under optimum conditions both of temperature and moisture, and is so constructed that it may be used indefinitely without becoming water-logged, thus resulting in a uniform quality of work at all times throughout the work period.

Yet another important object of the invention is attained in a combination ironing surface and iron rest, so constructed and supplied by and from a common thermal source, that both the ironing surface and the rest are maintained at temperatures such as to keep the work board under optimum operating conditions at all times, with the iron rest at a temperature which will prevent undesirable cooling or chilling of the iron between active work periods.

A still further important objective is attained in a novel material or composition of an absorbent fibrous nature, such that it possesses the property of instantly receiving such condensate

2

as necessarily results from the use of a steaming iron, and yet which by re-evaporation disposes of the condensate at least as fast as it would otherwise accumulate in the pressing support.

5 The foregoing and numerous other objectives will more clearly appear from the following detailed description of a single exemplifying embodiment of the invention, particularly when considered in connection with the accompanying drawing, in which:

Fig. 1 is a top or plan view of a pressing table embodying the present improvements;

Fig. 2 is a side elevation of the assembly of Fig. 1;

15 Fig. 3 is a front end elevation of the assembly; Fig. 4 is a transverse sectional elevation in a vertical plane, particularly as viewed along line 4—4 of Fig. 1, and

Fig. 5 is a sectional elevation in a vertical plane longitudinally of the assembly, particularly that portion along line 5—5 of Fig. 1.

20 Referring now by characters of reference to the drawing, although the specific form of subjacent support for the pressing table proper, does not 25 of itself form part of the present improvements, it may be noted for completeness as including a relatively heavy trifurcate base preferably of cast construction, the legs or feet of which are indicated at 10, located at the extremities of arms 14, the latter being surmounted by a top-open socket 12 provided with a set screw 13 which receives 30 a tubular column 14 carrying at its top a table-supporting plate member generally indicated at 15. Struts or braces, three of which are shown 35 and indicated at 16, are provided with formed ends (not shown) secured as will appear, to the board assembly as by bolts or rivets (not shown).

The pressing table assembly which may be said 40 collectively to include those parts above the support 15, includes by preference a relatively rigid, normally horizontal, stamped sheet metal body in the nature of a shallow pan, shaped by preference substantially as outlined by Fig. 1, and including a bottom portion 20. Marginally of the 45 body, and preferably over its full perimeter, extend vertical, right angular flanges 21. The depth of the shallow pan-like support is determined in accordance with the depth or thickness of the pressing board proper, later to be described, having regard also for the diameter of the preferably elongate heating elements later to be referred to. The rigidity of the pan-like body structure 20—21 is enhanced by an inverted angle or channel member, preferably the latter as shown and indicated at 22, this reinforcement

element extending longitudinally of and beneath the bottom 20 of the body over a portion of its length, and being welded thereto.

Distributed along the bottom 20 of the shallow pan-like body or frame of the board, is a length of heating coil, those portions of which indicated at 23, and lying inside of the body 20-21, are preferably continuous and are distributed in back-and-forth relation in such manner as evenly to impart heat to the different areas of the table. The heating element 23 may consist of enclosed electrical resistance units or other heated lengths of rod, but, by preference and as shown, it consists of one-quarter inch tubing of copper or some other thermally conductive metal. Whatever the nature of the heating coil 23, it is greatly preferred that this be of dry type, i. e. that it does not emit steam, nor otherwise introduce moisture below the ironing surface. The flexibility and thermal conductivity of copper tubing renders it especially useful for forming up the elements 23. In pressing boards of average commercial size, a length of the order of twenty to twenty-five feet of such tubing will be formed into back-and-forth, primarily longitudinal passes of the tubing. The heating element such as tubing 23 is preferably generally fixed in position along and to the bottom 20 of the body, as by a number of hold-down clips 25. These are conveniently of L shape form, including two short horizontal elements connected by a vertical leg, the horizontal parts being vertically spaced to an extent approximating the outside diameter of the tubing, and the lower portion of each clip being welded, for example, directly to the metal of the bottom 20 of the body or pan.

In the preferred arrangement the inlet end 24 of the tubing 23 is supplied by steam from a suitable boiler or steam generator (not shown) the outlet end of the tubing shown at 26 being connected directly or indirectly to a trap, boiler return system or otherwise connected in a suitable steam circuit. It may here be noted that the board assembly embodying the present improvements is particularly adapted for use with a steam system together with separator facilities, a pressing iron and adjunctive facilities therewith, all of the general order of those disclosed in U. S. Patent 2,071,128, issued to this applicant February 16, 1937, and entitled "Steam Separator and Superheater." When present improvements are utilized in and with a system of this order, the steam outlet or discharge 26 from the coil 23, may lead directly or indirectly to a trap such as 41 of the noted patent. In such an arrangement, the steam flow into, through and out of the distributed length of tubing 23, will take place in the directions indicated by the arrows (Fig. 1).

Directly overlying the several passes of the heating element 23 and preferably directly upon or substantially adjacent the tubing, is a pressing board or mat of fibrous nature later to be described, and indicated at 27. In order to assure the permanent planar characteristic of the board 27 and to keep it in a substantially horizontal position in the different parts of the board, the bottom 20 of the pan or body serves to carry a plurality of intermediate supports such as inverted channel elements 28. These are of a height or depth approximating, perhaps only slightly exceeding, the diameter of the tubing 23, and thus serve the purpose of longitudinally stiffening the pan-like body structure, and of relieving the tub-

ing of any superposed loading and otherwise probable distortion.

The depth or thickness of the absorbent board element 27, say one-half to one inch, is preferably such that it projects slightly above the upper margins of the flanges 21, thus precluding any possible interference with the margins of the ironing surface, by the flanges. As is customary in ironing or pressing operations, the element 27 may be wrapped within a fabric cover 30, the margins of which are brought down over the flanges 21, thence beneath the board and kept under moderate tension by any suitable means, for example, hooks 31 and cross tension springs 32.

15 At the rear end of the board assembly, and as a partial cover for this end of the board and serving as an iron rest, is a planar, normally horizontal member 33 preferably formed of a non-rusting, highly conductive sheet metal, such as 20 aluminum. The iron rest is conveniently provided with certain marginal flanges as may be required, these flanges being indicated at 34, but being omitted along that margin of the iron rest which lies immediately adjacent the pressing surface proper. The preferred relation between the surface of the iron rest 33 and the ironing surface identified with the adjacent portions of the cover 30, is or may be substantially a flush relation with some slight disparity in the levels of 25 the two surfaces.

Referring now more particularly to the nature and function of the board 27, this is preferably substantially rectangular in form, say over two-thirds of its length from back to front, although 30 toward the front or nose end of the board it is characterized by convergent sides similarly to the plan of the pan-like body, these convergent sides meeting in a rounded nose portion conforming by preference to the internal shape of the supporting body 20-21. Numerous experiments, extending over a number of months and involving trials of practically all fibrous materials possible to be employed to form the member 27, have resulted in a distinct preference for a mineral fiber, 35 and a further preference for a material possessing at least a moderate thermal insulation characteristic. It is necessary that the board proper or mat 27 be characterized by a reasonable power of fluid absorption or absorptive capacity; that 40 it be porous, first for absorbing a liquid such as water, and again for the purpose of readily giving off this moisture in the form of steam or vapor, when the board is heated. By preference also this element is of matted form, as distinguished from a woven fiber. It is a choice also 45 that this mat be imperforate, in the sense that it is not provided with any distinct, formed apertures or passageways therethrough. As a choice resulting from numerous trials, asbestos fibers of 50 a relatively coarse nature, say in which ninety percent of the fibers are of one-half to one inch in length, has proven superior to other materials, and to yield better results than asbestos fibers of lesser average length, and distinctly better than 55 any matted fibers of others materials.

It is obviously desirable to provide for a reasonable maintenance of form of the asbestos mat. This may be done by admixing a suitable binder therewith at the time of forming the mat. Such 60 binder should, however, be of a proportion distinctly minor in relation to the volume of the fiber, by preference and with best results, under ten percent by volume. A choice of binder evenly admixed with the asbestos while the binder is in 65 liquid or semi-liquid form is a thermosetting

resin, although other binding materials, for example, a proportion of Portland cement, plaster of Paris or other hydrosetting minerals, will suffice. Such binder should be kept for best results within the limits of proportion above stated.

The necessity for larger proportions of binder in the mat 27, is minimized in the present case by the firm subjacent support thereof, and the support of the mat over relatively close centers, as will be apparent from the locations of the channels 28 and the intervening tubing elements 23. Any tendency otherwise existing for the mat to spall off along the margins or corners is protected against by the vertical flanges 21, within which the mat fits by preference rather closely.

The selection of an insulation material and a preference for a mineral fiber such as asbestos, operates to effect a more even distribution of heat through the mat 27 than would be the case were a more shallow layer or even a layer of the same thickness of other materials, employed over the heating elements 23. In practice it has been determined that substantially all portions of the pressing surface are kept within a very few degrees of the same temperature, thus making for evenness and uniformity of the work. The selection of coarse asbestos, and the minimization of binder, further conduce to a desirable and permanent resilience.

The purposes and functions of the various elements are thought to have become fully apparent from the foregoing detailed description of a preferred form and arrangement thereof, but it may be noted that as steam is emitted from the iron (not shown) it is necessarily reduced in temperature by the work such as a fabric over which the iron is being operated. No matter how dry the original source of steam, at least some momentary condensation will occur in and below the fabric in work. The pressure in coil 23, hence the temperature thereof, is such that the mat and cover are at all times and in all parts of the board high enough so that, to the extent that any condensation actually occurs in the mat, re-evaporation quickly takes place as may actually be observed in practice. Thus the mat and cover are kept at all times under optimum conditions of temperature and moisture to produce the best quality of ironing operation and finish.

It should be noted as a particular advantage, that the heating coil 23 includes at least four partial lengths in the example shown, which extend directly under the iron rest 33, and thus serve to maintain the iron rest at a temperature not much if any lower than the best operating temperature of the iron. In this manner, there is avoided any tendency otherwise noted with cold iron supports to chill the sole plate between actual work movements.

It will now have appeared that the embodiment described serves fully to attain each of the several objectives hereinabove particularly pointed out, and others implied from the more detailed description. Such detail of description, relating solely to a selected example, should be understood in an informative rather than a limiting sense, because of the numerous variants possible within the scope of the claims hereunto appended.

I claim as my invention:

1. In a pressing board assembly for use with steaming irons, a relatively rigid table, a column

supporting said table, a foot structure on said column, strut braces, a plurality of which extend from a lower portion of the column to an outermost portion of the table, the table being in the form of a shallow metal pan including a bottom with upright bounding flanges, a steam heating coil of copper or like thermally conductive material entering at the back end of said board and extended in distributed fashion substantially over the bottom of the pan and having its exit at the entrance end of the board, the coil diameter being substantially less than the depth of the pan-like structure forming the table, fixed supports intervening the several passes of the distributed heating coil, an asbestos board overlying but substantially adjacent the heating coil, said board being formed of asbestos fibers and a binder retaining the fibers in a distinctly matted relation, and being highly thermally insulatively and moisture absorbent, a fabric cover over the asbestos board, the asbestos board being marginally retained in place by the marginal flanges of the pan and overlying the center and front areas only of the latter, an iron rest formed of a highly conductive sheet metal provided with downwardly extending side marginal flanges fitting between said upright flanges of the pan, the rest overlying a portion of the heating coil so as normally to be maintained in a heated condition thereby.

2. In a pressing board for use with a steaming iron, a supporting column, strut braces having their lower ends connected thereto and extending upwardly and outwardly therefrom, an elongated pan mounted on the upper end of said column and connected to the upper ends of said braces and provided with upright bounding flanges substantially about its entire periphery, a channel beam connected to the under side of said pan and extending longitudinally of the latter to reinforce the same, an elongated heating element within said pan and extending longitudinally of the latter for substantially the full length of the pan for several times, said element being shallower than the height of said flange, and an elongated asbestos board of a width fitting within said flanges, and stiffener elements secured to the inner surface of the bottom of said pan and extending substantially longitudinally of the latter to maintain it in planar form and being of a height to extend to at least the height of said heating element, said board supported on said stiffener elements to form a heating chamber between the under side of said board and the opposed surface of the pan bottom.
